CLAIM

The ornamental design for a front door panel for an automobile as shown and described.

DESCRIPTION

FIG. 1 is a left, front perspective view of a front door panel for an automobile showing my new design;

FIG. 2 is a left, rear perspective view thereof;

FIG. 3 is a left side view thereof;

FIG. 4 is a right side view thereof;

FIG. 5 is a front view thereof;

FIG. 6 is a rear view thereof; and,

FIG. 7 is a top view thereof.

The deemphasized/half tone portions of the front door panel for an automobile depict portions that form no part of the claimed design.
